UNITED STATES PATENT OFFICE

EDWARD J. VON PEIN, OF DAYTON, OHIO, ASSIGNOR, BY MESNE ASSIGNMENTS, TO THE NATIONAL CASH REGISTER COMPANY, OF DAYTON, OHIO, A CORPORATION OF MARYLAND

CASH REGISTER

Application filed November 16, 1923. Serial No. 675,158.

This invention relates to cash registers and is shown carried out in connection with a machine of the type shown in Letters Patent of the United States to Thomas Carney, No. 5 497,860, granted May 23, 1893, and to Edward J. Von Pein, No. 1,664,955, granted April 3, 1928.

The present application discloses an improved method of operating a plurality of printer impression hammers which structure is not claimed herein, but forms the basis of a division application, Serial No. 115,903, filed June 14, 1926.

To insure the proper operation of the machine an interlocking mechanism cooperates with the item keys and the printer operating mechanism. This interlocking mechanism is not claimed in the present application.

An object of the invention is to provide 20 auxiliary mechanism for operating the key coupler.

Another object of the invention is to provide an auxiliary means to restore the key coupler, in combination with means to assist 25 in operating the auxiliary means to relieve the drive shaft of a part of its operating load.

With these and incidental objects in view, the invention consists of certain novel features of construction and combinations of 30 parts, the essential elements of which are set forth in appended claims and a preferred form or embodiment of which is hereinafter described with reference to the drawings which accompany and form part of this specification.

Of said drawings:

Fig. 1 is a transverse section of the machine taken to the left of the totalizer.

Fig. 2 is a detail view of the driving connection between the key coupler and the cam shaft.

Fig. 3 is a sectional view taken between the right side frame and the printer frame.

Fig. 4 is a detail view of a part of the 45 receipt feeding mechanism.

Fig. 5 is a detail view of part of the key coupler auxiliary operating device.

Fig. 6 is a side elevation of the printer mechanism together with a part of the driving mechanism.

The machine disclosed, is in general substantially the same as that shown in the Carney and Von Pein patents referred to. Only so much of the old mechanism is disclosed as is necessary to give an understanding of these improvements, and the same will be described only in so far as is necessary to understand the specific invention here involved.

The machine includes a plurality of groups of amount or item keys, a totalizer, item entering, item printing and item indicating mechanism, and a driving means. The keyboard includes a plurality of groups of item or amount keys 20 pivoted on a transverse rod 21 mounted in the side frames of the machine. The rear ends of the keys engage a key coupler 22 which swings on trunnions 23 journaled in the side frames of the machine. Actuator controllers 24, connected to the rear ends of the keys, engage rods 25 carried by rocker frames supporting totalizer actuators 26.

The totalizer actuators are normally in mesh with gears 27 connected with the item printing wheels 28 (Fig. 6) by a tube line to set up the amounts represented by the keys depressed. The key coupler 22 carries a roller 29 mounted on its right hand side (Fig. 2) which cooperates with a slot in a driving double rack 30. The driving rack rotates a shaft 31 in the usual manner, as is well known in the art.

The amounts represented by the keys depressed are also entered in a totalizer 37 mounted in a frame 38 (Fig. 1) pivotally supported on trunnions 39 supported in a frame tie bar of the machine.

The totalizer is of a well known form for this type of machine and is provided with 90

totalizer elements having pinions 40 adapted to engage the actuators 26 at the proper time to enter the items registered by the keys.

Resting on the rear ends of the keys 20 are the usual tablet indicators 41 elevated to a display position when the keys are operated.

Key coupler device

Usually, in a machine of this type, the keys 20 are returned to normal positions after being depressed, by the weight of the key coupler 22, but in this machine, in addition to the weight of the key coupler, there is an auxiliary force assisting the key coupler in returning the operated keys to the normal positions.

Secured to key coupler trunnion 23 (Fig. 3) is an arm 42 with two projecting pins 43 and 44. As the key coupler is rocked and the arm 42 moved counter-clockwise, the pin 44 engages an upwardly extending arm 45 of a latch 46 and rocks this latch on its pivot 47 in a clockwise direction and releases a spring-tensioned lever 48 (Figs. 3 and 5) at the time the key coupler reaches the end of its upward movement. When the lever 48 is released, a projecting arm 49 is in contact with the pin 43 and assists the key coupler in returning to its normal position.

The spring-tensioned lever 48 is freely mounted on a stud 50 supported in the side frame of the machine and is rigidly connected to an arm 51 by a hub 52. This arm has a slot 53 into which is fitted an adjustable connection 36 for one end of a spring 54. The other end of the spring is connected to an arm 55 pivoted on a pin 56 supported in the side frame of the machine. This arm 55 carries a roller 57 normally engaging a depression 70 in a cam 58 pinned to a shaft 59 and which acts as an equalizing means in the rotation of this shaft. It will be hereinafter described.

The cam 58 also has a cam groove 60 into which a roller 61 carried by a pitman 62 projects. The forward end of this pitman has an elongated opening engaging a pin 63 projecting laterally from the arm 51. When the latch 46 is tripped, permitting the arm 51 to move counter-clockwise, the pin 63 will move to the right hand end of the slot in the pitman 62. During the operation of the driving shaft 59 the pitman moves the arm 51 clockwise to its normal position, whereupon the latch 46, under the tension of a spring 64, will engage a lip 65 formed on the lower end of the lever 48 to retain this lever until a following operation of the machine.

The spring 54 (Fig. 3) in addition to being a means for assisting the key coupler in its operation is also a means for equalizing the load on the driving shaft 59, the cam 58 being so formed that the tension on this spring varies during the rotation of the driving shaft 59. The depression 70 formed in the cam 58, is for the purpose of assisting the driving

shaft 59 to come to its normal or home position.

The driving shaft 59 (Figs. 3 and 6) is rotated in a counter-clockwise direction by a gear 71 secured to the shaft and in mesh with a pinion 72 secured to a sleeve 73 freely mounted on a stud 74 supported by the printer frame 75. The pinion 72 may be driven by a crank or electric motor, as illustrated and described in the Von Pein patent previously referred to.

Interlocking mechanism

As the item keys and the driving means are operated independently of each other, an interlock is provided between these two operating means. Secured to the right hand trunnion of the key coupler, outside the printer frame 75, is an arm 80 (Fig. 6) carrying a pin 81 which connects with an arm 82 freely mounted upon the trunnion 23. The lower end of the arm 82 carries a roller 83 engaging the upper edge 84 of a lever 85 fulcrumed on a pin 86 projecting from the printer frame 75.

As the arm 82 is rocked counter-clockwise by the key coupler, the lever 85 is moved counter-clockwise on its pivot and causes the rearwardly extending arm 88 of the lever 85 to move out of the path of a lug 89 secured to the gear 71.

As the forward end 90 of the lever 85 moves downwardly it will pass a pin 91 carried by an arm 92 always under spring tension to move in a counter-clockwise direction. Therefore, as the end 90 of the lever 85 reaches a point below the pin, the lever will assume a position with the pin over the end of the lever 85 and retain the lever in this position while the key coupler arm 82 returns to its normal position.

With the lever 85 in this operated position the driving means previously referred to is free to rotate the driving shaft 59. As this shaft rotates counter-clockwise, an extension 93 of the lug 89 engages the lower arm 94 of the lever 85 and forces this lever to return to its normal position, in which position the driving means is disabled by the lug 89 again being in contact with the arm 88.

Another interlocking feature is provided, which allows but one operation of the item keys to each operation of the driving means. A spring-actuated arm 95, freely mounted upon the pin 86, has a laterally projecting pin 96 engaging a shoulder formed on the lever 85. As the lever 85 is moved counter-clockwise to release the cam shaft 59, as previously described, the arm 95 contacts the pin 81 and rests upon this pin during the counter-clockwise movement of the arm 82. During the return or clockwise movement of the arm 82, the arm 95 will continue its counter-clockwise movement until the pin 96 again

engages the shoulder on the lever 85, in which position an end 97 of the arm 95 will be in the path of the pin 81 to prevent a second movement of the arm 82 by the operation of an item key. The return of the lever 85 to its normal position will return the arm 95 to the position shown in Fig. 6.

Printing mechanism

10 Only so much of the printing mechanism is disclosed in Fig. 6 as enters into the invention here involved, the printer being fully described and illustrated in the Von Pein patent previously referred to. The type 15 wheels 28, previously described, print the items as they are entered, both upon a record strip 103 retained within the machine and an issuing strip 104.

The record strip 103 is fed from a supply 20 roll 105 around guide rollers 106 and onto a receiving roll 107 in the usual manner. The issuing strip 104 is fed from a supply roll (not shown) around a guide roller 108 and between a feeding roller 109 and a tension 25 roller 110. The tension roller 110 is carried on a pivoted arm 111 and held in contact with the feeding roller 109 by a spring 112.

The feeding roller 109 moves counter-clockwise at each operation of the machine 30 and retrograde motion of this roller is prevented by a spring-actuated pawl 113 which engages a ratchet wheel 114 secured to the feeding roller 109. This feeding roller is secured to a shaft 115 journaled in the 35 printer frame 75. The feeding roller is operated by a spring-tensioned pawl 116 (Fig. 4) cooperating with a ratchet wheel 102 pinned to the shaft 115. The pawl is pivoted on an arm 117 freely mounted upon 40 the shaft 115. Secured to this arm is a pinion 118 which is in mesh with a segment arm 119 pivoted on a stud 120 supported by the frame work of the machine. This arm is oscillated at each operation of the machine 45 by two cams 121 and 122 engaging rollers 123 and 124 respectively mounted upon studs carried by the segment arm 119.

The records are made upon the record strip 103 and the issuing strip 104 by the aid of an 50 inking ribbon 125 which passes partly around a feeding roller 126, over guide rollers supported in the printer frame and under a tension roller 131 carried by an arm 132 pivoted at a point 133.

55 The impressions upon the record strip and the issuing strip are made simultaneously by spring-actuated impression hammers 134 and 135. The impression hammer 134, which causes the impression to be made upon the record strip 103, is pivoted upon a stud 136 mounted in the printer frame and has a formed ear 137 engaging a spring plunger 138 supported in a bracket 139 secured to the printer frame. A downwardly extending 60 arm 140 of the impression hammer 134 con-

tacts a pin 141 (Figs. 3 and 6) to return and retain the impression hammer 134 in its normal position after an operation.

The impression hammer 135, which causes the impression to be made upon the issuing strip 104, is pivoted upon a stud 146 supported by the printer frame and has a rearwardly extending arm with a formed ear 147 engaging a spring-actuated plunger 148 supported by a bracket 149 secured to the printer frame. An upwardly extending arm 150 of the impression hammer 135 contacts a pin 151 which returns and maintains the impression hammer 135 in its normal position after an operation of the machine.

The pins 141 and 151 are carried by a lever 152 fulcrumed on a stud 153 supported by the frame of the machine. This lever 152 has a flat sided pin 154 (Fig. 3) which engages a spring-pulled latch 155 pivoted on a stud 156. This latch retains the lever 152 in its normal position, as shown in Fig. 3, and the impression hammers 134 and 135 under spring tension, as shown in Fig. 6. As the shaft 31 (Fig. 3) rotates counter-clockwise during 90 the operation of any item key 20 (Fig. 1), a pin 158 carried by a disk 157 secured to the shaft engages an arm 159 extending downwardly from the latch 155, and rocks the latch 155 clockwise on its pivot to disengage it from the flat sided pin 154. At this time a finger 160 on the lever 152 engages a cam 161 and retains the impression hammers until the finger 160 drops off at the shoulder 95 162 of the cam, when the spring plungers 138 and 148 (Fig. 6) operate the impression hammers 134 and 135 to print upon the record strip 103 and the issuing strip 104.

The finger 160 on the lever 152 drops quickly from the high part of the cam 161 to the 100 low part, to afford a springing hammer blow upon the type carrier.

During the operation of the driving mechanism the impression hammers are returned to their normal positions by an upwardly 110 extending arm 168 of the segment arm 119 (Fig. 3). As this arm is moved counter-clockwise the arm 168 engages the flat sided pin 154 and returns the lever 152 to a position to enable the latch 155 to again engage 115 the flat sided pin 154 and retain the impression hammers in their normal positions until the next operation of the machine.

Operation

In an operation of the machine the operator depresses the item keys 20 corresponding to the value of the transaction, and allows them to return to normal positions. This causes the item to be entered in the totalizer, 125 displayed by the indicators, and printed on the record strip and the issuing strip, and releases the driving mechanism which is then operated to complete the transaction by feeding the issuing strip and restoring the im- 130

pression hammers to normal positions, and operating other parts of the mechanism.

While the form of mechanism herein shown and described is admirably adapted to 5 fulfill the objects primarily stated, it is to be understood that it is not intended to confine the invention to the one form or embodiment herein disclosed, for it is susceptible of embodiment in various forms all coming within 10 the scope of the claims which follow.

What is claimed is:—

1. In a machine of the class described, in combination, a plurality of lever keys, a key coupler, a driving shaft, a swinging member 15 adapted to be moved in one direction by a spring to cooperate with said key coupler in returning said keys to normal positions, a separately mounted latch member normally retaining said swinging member, a member 20 secured to said key coupler and adapted to release said latch, and a pitman operated by said driving shaft for returning said swinging member to normal position.

2. In a machine of the class described, the 25 combination of manipulative means; a rockable member operated thereby; rotatable means; a movable member normally under spring tension; a separately mounted latch to retain said member in normal position; 30 means, rigid with the rockable member, and having a projection to operate the latch to release the movable member; and a device operated by said rotatable means to return the movable member to normal position.

3. In a machine of the class described, the 35 combination of manipulative means; a rockable member operated thereby; a drive shaft, a normally restrained member having a lip, adapted, when released, to restore the rockable member to its normal position; a spring 40 adjustably connected to the normally restrained member; means, including a separately mounted notched latch normally engaging the lip on the normally restrained member; means on the rockable member 45 adapted to trip the latch; means to restore the normally restrained member to its normal position; and means operated by the drive shaft to operate the restoring means, to 50 increase the tension of the spring at a certain time, and to release the spring, whereby the increased tension assists in operating the restoring means, thus relieving the drive shaft of a part of the operating load.

4. In a machine of the class described, the 55 combination of manipulative means; a rockable member operated thereby; rotatable means; a movable member normally under spring tension; a separately mounted latch to retain said member in normal position; a bell crank rigid with the rockable member; 60 a projection on the bell crank extending into the plane of the latch to actuate the latch 65 when the rockable member is operated by the

manipulative means, to release the movable member; another projection on the bell crank extending into the plane of the movable member; a finger on the movable member to contact the second named projection to restore the bell crank and rockable member to their normal positions when the movable member is released by the latch; and means to restore the movable member to its normal position.

In testimony whereof I affix my signature.

EDWARD J. VON PEIN.
